UNITED STATES PATENT OFFICE.

THOMAS H. CAMPBELL, OF ALLEGHENY, PENNSYLVANIA.

DUMB-BELL.

SPECIFICATION forming part of Letters Patent No. 416,565, dated December 3, 1889.

Application filed September 24, 1889. Serial No. 324,875. (No model.)

To all whom it may concern:

Be it known that I, THOMAS H. CAMPBELL, a citizen of the United States, residing at Allegheny, in the county of Allegheny and State of Pennsylvania, have invented certain new and useful Improvements in Dumb-Bells, of which the following is a specification, reference being had therein to the accompanying drawings.

10 It is customary in using dumb-bells for athletic exercise to commence the practice with the lighter weights, gradually changing to the heavier weights as the muscles become more and more developed. As usually constructed the weight of each dumb-bell is constant and cannot be changed, and the bells also vary in size, according to the weight, necessitating a change to a new set whenever a change of weight is desired, which is inconvenient and expensive.

15 The object of my invention is to obviate these objections and provide a dumb-bell of a determined size, the weight of which may be increased or diminished at will without altering the size or shape thereof. These objects are attained by the means illustrated in the accompanying drawings, in which—

20 Figure 1 represents a view, partly in section and partly in elevation, of a dumb-bell constructed according to my invention. Fig. 2 represents an end elevation thereof with a cap forming a portion of the bell removed; and Fig. 3 represents a detail view, in cross-section, showing a portion of the bar and one 25 of the spheres, and a wedge for securing the sphere on the bar.

25 Referring to the drawings, the letter A indicates the bar or handle of the dumb-bell, which is preferably constructed of wood, the central portion being formed to fit the hand when grasped, as usual. At each side of said central portion the bar or handle is formed with concave shoulders *a*, the curve of which corresponds to the curve of the exterior of the balls or spheres, so as to form accurate 30 seats therefor. The portions of the bar or handle at each side of the shoulders are equal in length to the diameter of the balls, which are indicated by the letter B. The said balls or spheres are constructed preferably of cast metal, and are hollow, being provided with diametrically-opposite openings *b*, in which

35 the smaller portions of the bar or handle at each side of the shoulders fit, the ends of the said bar or handle being flush with the outer surfaces of the balls or spheres, as shown. Near each end of the bar or handle it is grooved longitudinally for a short distance, as indicated by the letter *c*, and contiguous to the said groove, when the balls or 40 spheres are in place, the outer aperture in said ball or sphere has formed at its edge a semicircular recess *d*, which, in connection with the groove *c*, forms a passage through which a suitable filling material for weight- 45 ing the dumb-bell may be passed.

50 The letter *g* indicates two caps, which are slightly dished or concaved on one side, and which may be secured to the ends of the bar or handle by means of screws *h*, with the dished sides bearing against the outer surfaces of the balls or spheres, the caps serving the double purpose of confining the balls upon the bar and closing the passage-way through which the balls are charged.

55 The relative dimensions of the handle or bar and the balls may be such as convenience or taste may dictate; but I prefer to have the balls equal in diameter, each to be one-third the length of the bar or handle, which will 60 form a well-balanced article, aesthetical in appearance and convenient to handle.

65 In order to fasten the balls securely to the bar or handle, the ends thereof are split longitudinally for a short distance, and wedges *i* are inserted, which spread such ends and cause them to bind tightly in the outer bevelled apertures of the balls or spheres.

70 Any suitable material—such as sand, shot, or granules—may be employed for weighting the balls or spheres.

75 Having thus described my invention, what I claim, and desire to secure by Letters Patent, is—

80 1. A dumb-bell consisting of two hollow spheres mounted on a bar or handle and provided with passages for filling said spheres with a weighting material, and a cap for covering the same, substantially as specified.

85 2. The combination, with the bar or handle of a dumb-bell having concave shoulders and provided with longitudinal grooves at the ends, of the diametrically-perforated spheres having recesses at the edges of their

outer openings contiguous to said grooves, and forming with the same passages for the weighting material, and the caps secured to the ends of the said bar or handle, substantially as and for the purposes specified.

3. The combination, with the bar or handle of a dumb-bell provided with shoulders and grooves, as described, of the spheres diametrically perforated and recessed at the edges of the outer perforations, the wedges set in

the ends of the bar or handle, and the caps secured to the ends thereof, substantially as and for the purposes specified.

In testimony whereof I affix my signature in presence of two witnesses.

THOS. H. CAMPBELL.
